MOTORIZED DRIVE

Robert E. Manley, York, Pa., assignor to Manley Products Corp., York, Pa., a corporation of Pennsylvania

Application December 16, 1933, Serial No. 702,771

26 Claims. (Cl. 74—142.13)

This invention relates to driving mechanism for motorizing such machines as lathes, shapers, milling machines, cone-drive screw machines and in fact any machine which is driven from overhead shafting by means of cones and has for its principal object the provision of a motorized drive utilizing the existing overhead cone and being adaptable to use with different machines.

10 A further object of the invention is the provision of a simple and efficient merchandisable unit which can be made up for a number of different sizes of machines and be sold direct to the factory owner without the need for any dimensions being given by him except a general idea of the machine, for example, it would be sufficient for the purchaser to say he had a 16" lathe.

15 A further object is to provide a simple motorizing unit which will include ready means for reversal in case the lathe to which the unit is applied is not equipped with a chasing device.

20 Other objects of the invention include provisions for shifting the belt with ease, speed and safety; permitting a tighter belt drive than is possible with overhead shafting, thus increasing production since it is impossible to shift the belt with ordinary drives if the belt is tight; and provision of a unit which avoids all binding action such as occur when the unit has but one stud.

25 There are in use in this country great numbers of machines which are driven from shafting and which could be placed more conveniently and made far more economical in use if some simple way could be provided to eliminate the overhead shafting. While it is possible today to buy a motorized unit for any one particular machine and in fact two concerns are at present making motorized drives for fairly general use, these devices require that the purchaser give eighteen different measurements in one case and twenty in the other, from which the drive is built at the factory, requiring a delay of about six weeks.

30 A very important object of the present invention is to provide three or four sizes of motorized unit which can be placed in boxes and sold to the owners of different sizes of machines, for example, the statement that the machine for which the unit is desired is a 20" lathe is amply sufficient, for the unit adapted to this size is equally adapted to a lathe varying anywhere from 18 to 24" in swing. All the parts of the present units are adjustable so that with the horsepower requirement given, a unit can be shipped direct to

the shop from the factory and can be installed without difficulty.

In the drawings:—

Figure 1 is a perspective view of my unit in place on a lathe.

Figure 2 is a front elevation.

Figure 3 is a side elevation.

In Figure 1 I have shown as an embodiment of my invention the unit as applied to a lathe 10, the rear web 11 of which is almost invariably free of obstructions just behind the cone pulley 12 and this portion of the mechanism is therefore used on which to mount the supporting brackets 15 as, for example, by means of the screws 14. The bracket 15 will vary very materially in size, shape and location when used with other devices such as a saw in which case it will extend from one end of the frame; a drill, in which case the bracket will be secured to a bed plate; a shaper, or boring machine, in which case not infrequently the pedestal 20 may be secured to the floor more conveniently than to any portion of the frame. In the lathe however, the rear web is always available and would invariably be used. The bracket 15 has a finished upper surface 16 and is slotted to receive the bolt 17 of a post socket 18, receiving a post 20 which forms the main support for the unit. At the top of the post a post arm 21 is secured and this carries a horizontal rock shaft 23 which in my preferred construction is rigidly held in the post arm 21.

25 At or near each end of the rock shaft is placed a brace bracket, for example, 25 and 26 having downwardly extending offset portions 27 ending in hubs 29, each hub being securely fastened to a tie rod 30 as by the set screws 31 and the upper hub portion of the brace bracket is made fast to the rock shaft by a similar countersunk set screw 32.

30 The normal oil hole of the two pedestals of the lathe is enlarged to receive a supporting member for the front ends of the two tie rods 30, such member conveniently being built up of a nipple 34 carrying an anchor fitting 35 in which is threaded a service L 36 to receive the grease cup 37 which has been removed from the pedestal. The L, the anchor fitting and the nipple provide a thru passageway for the oil or grease so that the oiling of the bearings is substantially unchanged. A pair of knuckle joints 38 and 39 receive between them a right and left stud 40 having a central hole 41 therethru for convenient turning of the stud so as to alter the distance between the knuckle joints, this function being necessary to secure the desired tightness of the 45 50 55

belt 43 which drives the cone pulley 12. At the upper portion of the knuckle joint 39 is secured an eccentric shaft bearing 44 which has a downwardly extending lug 45 extending between the 5 two ears 46 of the knuckle joint 39 and has extending from its rear a socket 47 into which is secured the front end of a proximate tie rod 30, as by the set screw 48. The parts mentioned thus far form a rigid support on which is pivoted 10 a superstructure consisting of a frame carrying the driving mechanism.

The main portion of the rocking frame is made up of eight channel members arranged in pairs, the larger channels 50 running from front to back and are spaced apart the correct distance by the usual filler blocks and pipe spacers. The transverse channels 51 are mounted in pairs across the main channels 50 and likewise have spacers 52 for holding these motor rail channels the proper distance apart to receive snugly the 15 bolts 53 and 54 securing, respectively, the legs 56 of the electric motor 57 and the clips 58 which join the pairs of channels. At the front end the 20 rocker frame channels 50 pivotally receive the upper hub of the eccentric strap member 60 and toward the rear these rocker frame channels each carry a rocker shaft bearing 63 fast to the 25 channels as by the clips 64 and the bolts 65. In the preferred modification the rocker shaft 23 30 does not turn but the bearings 63 do turn on this shaft, being held against longitudinal or side to side movement by two or more set collars 66 fixed to the rock shaft 23.

A drive pinion 70 is supplied with the unit to be secured to the armature shaft 71 of the motor 35 57 which usually is not supplied, there generally being available at the place of installation a suitable motor. The drive pulley 70 drives a plurality of V belts 72 and drives the pinion shaft 75 by means of a pulley 74. The main driving pinion 76 fast on shaft 75 meshes with gear 77 40 on counter shaft 80 supported preferably by the roller bearings 81 in bearing housing 82 resting upon the rocker frame channels 50 and secured 45 to them as by the screws 84 which are threaded into the bearing housing 82 and engage plate washers 86 below the bottom flanges of the two channels of each pair.

It is my preference to enclose the motor belt 50 or belts 72 with a guard 88 and to provide a similar guard 89 for the gears 76 and 77. Both of these are preferably fixedly secured to the left front rail as by the brackets 90 and 91 but in the larger sizes while I secure the gear guard to the 55 rocker frame channels or rails 50 as by the boss 90, I find it a bit more convenient, especially in the larger sizes, to connect the rear of the belt guard to the motor rail channels, as, for example, by the lug 91 integral with the guard, the slotted link 92, bolt 93, and link bracket 94 secured to the motor rail channels, this construction probably being most clearly illustrated in Figure 1.

On the eccentric shaft 100 which may oscillate in the two eccentric shaft bearings 44 in which 60 it turns with considerable friction regulated by the screw 101 in the split jaws of the bearing, is a pair of eccentrics 102 turning within the eccentric straps 60. The eccentric lever 104 is secured to the eccentric shaft as by the set screw 70 105 and the hub 106 of the eccentric 102 is similarly secured as by the set screw 107. In the position shown in the drawings the eccentric lever is in normal working position at which time 75 the countershaft 80 carrying the upper cone pulley 109 is in its highest position and the belt

43 is therefore tightest and the eccentric is on dead center so that there is no tendency for it to turn. Should any adjustment be needed this is taken care of by turning the right and left threaded stud 40. When the eccentric lever is 5 moved downwardly the belt 43 is loosened materially so that it is extremely simple to shift the belt in usual manner. During the movement of the lever 104 the entire superstructure turns about the axis of the rock shaft 23 with the two 10 rocker shaft bearings 63.

In installing this device on an existing lathe, for example, the upper line shaft is removed, saving the upper stepped cone pulley 109 with its shaft 80 which doubtless will need to be turned 15 down on its two ends to fit the roller bearings 82. The oil or grease cups 37 are now removed from the lathe pedestals and the hole is tapped to larger size to receive the close nipple. The grease cup 37 from the machine is now screwed 20 into the service L 36 completing the front post. The rear web of the lathe is tapped to receive the bolts 14 and this secures the bracket 15 in place with its upper finished surface 16 exactly level, the lathe itself naturally being level 25 and having its center line precisely horizontal. The post socket with the main post 20 is adjusted to proper distance from the lathe so that this main post which supports practically all the weight shall be as near as possible in line with 30 the center of gravity of the superstructure. The rocker shaft bearings 63 are placed in a proximate position and the frame consisting of the eight channels is assembled on the rocker shaft bearings. It is obviously quite immaterial 35 whether the rock shaft turns with the rocker shaft bearings or not but I prefer that the rock shaft shall be held stationary as this seems to give a more sturdy structure. The counter shaft axis 80 is next tested to insure that it is precisely 40 parallel with the axis of the lower unchanged stepped pulley 12. The two right and left studs 40 each have the so-called micrometer threads so that adjustment can be made precise. The tie rods 30 are furnished a bit longer than usually 45 necessary as is the rock shaft and it is convenient when the device is installed to cut off the unnecessary ends of the tie rods beyond the 50 brace brackets 25 or 26, as the case may be, so as to give a rigid structure consisting of the three posts, the two tie rods, the rock shaft and the brackets 25, 26 and 44.

It will be noted that every portion of the device is adjustable, consequently once the horsepower of the motor is given a unit can be furnished without any other information. It is much more usual to specify the size of the lathe 55 because the horsepower needed for the lathe is known as soon as the size is known.

The drive is from the motor pulley 70, thru the belt 72, to the pulley wheel 74 which is on the same shaft as the pinion 76 which meshes with gear 77 on counter shaft 80 which is the shaft of the cone pulley 109 which is connected by a 60 belt 43 with the cone pulley 12 of the lathe. In the position shown in the figures the belt is taut, the eccentrics 102 being at their highest point and the rails 50 being substantially horizontal. Should it be desired to increase or decrease the 70 tightness of the belt when the parts are in this position, the two studs 40 are turned by means of a rod placed thru the hole 41, care being taken to keep the axis of shaft 80 exactly horizontal. When the eccentric lever 104 is moved 75

5 downward, the upper superstructure is moved as a unit about the axis of rock shaft 23 and the belt 43 is made very loose so that it can readily be shifted to a different step of the cone and when in proper position the lever 104 is raised where it remains as there is no tendency for it to move when at or near dead center position. The bolt 101 may be used however, to increase or decrease the friction between the eccentric shaft 10 100 and its bearings 44.

10 In some cases I have found it practical to eliminate the pinion shaft 15, as for example, in devices which like a wood lathe require a high speed countershaft. In these cases the motor 15 armature pulley 10 thru the belt or belts 12 drives a fairly large pulley mounted directly on the countershaft, thus eliminating the usual reduction gearing.

15 The guards 88 and 89 are preferably tied together as by a bracket 111 adjustably secured to the guard 89 by means of a set screw 112 and carrying at its opposite end a bolt 113 which engages in the slot 114 of the forwardly projecting bracket 115 which bracket is adjustably secured to the guard 88 by the screw 116. This construction gives the necessary rigidity without making this part of the machine any less flexible for adjustment than the other parts whereby the entire mechanism may be adapted to almost any type of power driven machine found in a machine shop.

20 What I claim is:

25 1. In a device for motorizing a line shaft machine of the belt and pulley driven type, an adjustable support for accommodating electric motors of various sizes, a counter shaft adjustably secured to said support and adapted to receive a drive pulley for driving the power receiving pulley of the machine, means for mounting said support and shaft to turn as a unit about an axis fixed with respect to said machine so that the axis of the counter shaft is constantly parallel with the axis of the power receiving pulley of the machine, means adapted to engage a fixed portion of the machine, and unit raising mechanism spaced from said fixed axis and engaging said last mentioned means for moving the unit about its pivotal axis to alter the distance between the shaft and the axis of the cone pulley.

30 2. The device of claim 1 in which the unit raising mechanism includes a pair of spaced eccentrics.

35 3. The device of claim 1 in which the electric motor support and the means for mounting the members to turn as a unit comprise a plurality of longitudinal and a plurality of transverse rails rigidly but adjustably secured together to form a frame of adjustable dimensions, the distance between the longitudinal rails being determined by the size of the motor supported and the distance between the transverse rails being approximately determined by the length of the counter shaft.

40 4. The device of claim 1 in which the means for supporting the members to turn as a unit includes two spaced rails adjustably secured to said motor support for any chosen spacing as determined by the size and type of machine being motorized, and the unit raising mechanism includes a plurality of eccentrics to raise and lower the ends of the rails.

45 5. In a device for motorizing a line shaft machine of the belt and pulley driven type, an adjustable support for an electric motor comprising two transverse members, a pair of rails to which

5 each of said members is adjustably secured to form a frame, a counter shaft mounted upon said frame and adapted to receive a drive pulley for driving the power receiving pulley of the machine, a rock shaft supported from said machine so that its axis is held parallel to the center line of the machine and at a fixed distance therefrom, means adjustable on the frame and with respect to the rock shaft for pivoting the frame to move about the axis of the rock shaft, a plurality of front posts each extensible and secured to a fixed portion of the machine, and a plurality of unit raising mechanisms engaging said front posts and said frame for moving the unit about the axis of the rock shaft so as to alter the distance between the counter shaft and the axis of the pulley of the machine.

10 6. The device of claim 5 in which the machine is a cone driven lathe, the front posts each rise from a pedestal of the lathe, and the means for 20 moving the unit about its pivotal axis includes a pair of eccentrics mounted on a single shaft.

15 7. The combination with a cone driven lathe, of a rock shaft adjustably mounted upon the lathe with its axis parallel to the center line of 25 the lathe and at an adjustable distance therefrom, a rocking frame adapted to oscillate about the axis of the rock shaft, an electric motor adjustably carried by said frame, a cone pulley adjustably mounted on said frame with its axis 30 parallel to the axis of the rock shaft, means operatively connecting the motor and the counter shaft, and means engaging a fixed portion of the lathe for raising and lowering the end of the frame carrying the counter shaft, said means 35 comprising an extensible front post rising from each pedestal of the lathe, an eccentric shaft mounted in said posts, and means connecting the eccentric with the forward end of said rocking frame.

40 8. The combination with a cone pulley driven machine, of a frame pivoted about an axis fixed with respect to the machine, a driving cone pulley rotatably mounted on the frame, a belt connecting said pulleys, means for rotating the driving 45 pulley, means for moving the frame about its axis to loosen and tighten the belt, and tensioning means for increasing or decreasing the tightness of the belt when the frame moving means is in position to tighten the belt, said means for 50 moving the frame, together with the tensioning means forming an articulated connector between the free end of the frame and the machine, said connector including an eccentric and its strap.

45 9. In combination, a bracket adapted to be rigidly secured to a fixed portion of a pulley driven machine, a support adjustably mounted in said bracket, a frame carried by said support, and oscillatable about an axis which is adjustable with respect to said support, a pulley mounted 60 on said frame with its axis parallel to the axis of the pulley of the machine, and means carried by the frame for driving said pulley.

55 10. In combination, a rock shaft, means for mounting said rock shaft upon a pulley driven 65 machine, a pair of spaced members adjustable along said shaft and oscillatable about the axis of said shaft, a channel adjustably secured to each member, means for connecting the two channels to form a frame, a pulley mounted on 70 said frame, and means adjustably carried by said frame for driving said pulley.

60 11. The combination with a cone pulley driven lathe of a support rigidly but adjustably secured to said lathe at the rear thereof, a rock shaft 75

- adjustably carried by said support with its axis above, to the rear of, and parallel to the axis of the lathe, a frame pivoted to move about the axis of the rock shaft and carrying a motor, a driving cone pulley and reducing mechanism between the motor and driving pulley, a belt connecting said driving pulley with the pulley of the machine, and means for raising and lowering the free end of the frame to cause the belt to engage firmly the two pulleys and to cause the belt to become loose for shipping, said means including a manually movable handle at the front of the machine in convenient reach of the operator.
12. The device of claim 11 in which the frame includes a plurality of bearing members adjustably mounted along said rock shaft, a pair of rocker frame channel members adjustably secured to each bearing member, and a pair of motor supports each consisting of a pair of motor rail channels rigidly spaced apart to receive between them securing members for holding the motor rail channels to the rocker frame channels.
13. In a device for motorizing a line shaft machine of the belt and pulley driven type, a frame for an electric motor and for a counter shaft comprising a base of two relatively adjustable pairs of metal beams of standard rolled shapes each member of each pair having an upright portion rising from a horizontal flange, a bearing on each pair, means between the members of each pair for adjustably securing the bearings thereto, a counter shaft in said bearings, a motor support comprising two relatively adjustable pairs of channel irons adjustably spaced from said shaft, means for adjustably securing said pairs of channel irons to the first mentioned pair, the channel irons of each pair having their webs upright and their flanges opposed, means for connecting the channel members of each pair rigidly together with the edges of said opposed flanges in spaced relation, and adjustable means between and engaging the upper flanges of the channel irons for adjustably securing an electric motor thereto.
14. The device of claim 13 in which a second pair of bearings is adjustably secured to the base pairs for pivotally mounting the frame.
15. The device of claim 13 in which a second pair of bearings is adjustably secured to the first mentioned pairs of beams, a rock shaft journaled in said second pair of bearings, and a post adjustably secured to said rock shaft for supporting the frame on a line shaft machine.
16. The device of claim 13 in which a second set of bearings is adjustably secured to the first mentioned pairs of beams adjacent one end of and on the side opposite the counter shaft bearings, a rock shaft in said second set of bearings for pivotally supporting the frame, a pair of braces secured to the opposite end of said first mentioned pairs of beams, a pair of rigidly connected eccentrics carried in said braces and means adapted to engage a line shaft machine for supporting said eccentrics.
17. A device for motorizing a line shaft machine comprising a horizontal frame for adjustably supporting an electric motor and a counter shaft, downwardly extending aligned brackets adjustably secured to the frame near one end, for engaging a rock shaft, a pair of spaced eccentrics, downwardly extending aligned brackets adjustably secured to the frame at the other end for engaging said eccentrics, a shaft for rigidly connecting said eccentrics to turn in unison, means for rotatably mounting the eccentric shaft on a line shaft machine, means for adjustably supporting the rock shaft and tie rods for adjustably connecting the rock shaft with the eccentric shaft.
18. In a device for motorizing a line shaft machine of the belt and pulley driven type, a support for an electric motor, a counter shaft adapted to receive a drive pulley for driving the power receiving pulley of the machine, means for mounting said support and shaft to turn as a unit about an axis fixed with respect to said machine so that the axis of the counter shaft is constantly parallel with the axis of the power receiving pulley of the machine, spaced posts rising from fixed portions of the machine, and unit raising mechanism spaced from said fixed axis and positioned by said posts, for moving the unit about its pivotal axis to alter the distance between the shaft and the axis of the pulley.
19. In a device for motorizing a line shaft machine of the belt and pulley driven type, a support for an electric motor, a counter shaft carrying a cone pulley for driving the power receiving cone pulley of the machine, a pair of spaced bearings in which said counter shaft turns and being adjustably mounted for movement toward or away from each other and toward and away from the motor whereby to accommodate shafts, pulleys and motors of different dimensions so that said support and shaft are adjustably mounted relative to each other but to turn as a unit about an axis fixed with respect to said machine, means adapted to engage a fixed portion of the machine, and unit raising mechanism spaced from said fixed axis and positioned by said last mentioned means for moving the unit about its pivotal axis to alter the distance between the counter shaft and the axis of the driven cone pulley.
20. In a device for motorizing a line shaft machine of the belt and pulley driven type, a support for an electric motor, a counter shaft adapted to receive a drive pulley for driving the power receiving pulley of the machine, means for mounting said support and shaft to turn as a unit about an axis fixed with respect to said machine so that the axis of the counter shaft is constantly parallel with the axis of the power receiving pulley of the machine, two separately extensible posts, each engaging a fixed portion of the machine, and unit raising mechanism spaced from said fixed axis and positioned by said posts, for moving the unit about its pivotal axis to alter the distance between the shaft and the axis of the pulley.
21. A motorized line shaft machine comprising a lathe having a cone pulley, a support for an electric motor, a countershaft, a driving cone pulley on said counter shaft, means for adjustably mounting said support and shaft relative to each other but to turn as a unit about an axis fixed with respect to said machine so that the axis of the counter shaft is constantly parallel with the axis of the driven cone pulley, a short belt connecting the two cone pulleys for driving the lathe and two posts, one rising from each of the lathe pedestals and having a right and left threaded stud whereby the height of either post may be adjusted with extreme accuracy and independently of the other post and unit raising mechanism, positioned by said posts, for altering quickly the distance between the axes of the cone pul-

leys without disturbing the adjustment of either or both of the two posts.

22. In a device for motorizing a line shaft machine of the belt and pulley driven type, a support for an electric motor, a counter shaft adapted to receive a drive pulley for driving the power receiving pulley of the machine, a rock shaft parallel to the driven pulley of the machine, a belt engaging said pulleys, means for mounting the support and countershaft to turn as a unit about the axis of said rock shaft, means engaging a fixed portion of the machine, a plurality of braces extending from the rock shaft to the last mentioned means, and unit raising mechanism spaced from the axis of the rock shaft and positioned by said braces and said means, for moving the unit about the axis of the rock shaft to alter the distance between the constantly parallel axes of the two pulleys, to facilitate shifting of the belt.

23. In combination, a machine having a driven cone pulley, a support pivoted about an axis fixed with respect to the axis of the pulley, a drive cone pulley on said support, four members pivoted to each other in pairs, one of each pair being pivoted to the machine and the other to the support, a belt connecting the two cone pulleys, means at the junction of the members for quickly moving the axes of the cone pulleys to

ship the belt, and a positive telescoping threaded connection in one member of each pair for adjusting the tension of the belt when in driving position.

24. A device for motorizing a line shaft machine comprising a frame, means for rigidly connecting said frame to such a machine, said frame having a rock shaft at one end, a second frame mounted on said rock shaft for supporting a motor and a counter shaft, means spaced from the rock shaft for connecting the first frame to the second frame for moving the latter about the rock shaft and tensioning means incorporated in said first mentioned means for adjusting the distance between said first frame and said line shaft machine.

25. The device of claim 24 in which said first frame is substantially quadrilateral in form comprising said rock shaft on one side, a rotatable shaft on the other side for operating said frame moving means, bars on the remaining sides and means for adjustably connecting said shafts and bars to provide a frame of adjustable dimensions to fit various sizes and kinds of machines.

26. The device of claim 24 in which each frame consists of fabricated parts adjustably connected together whereby to accommodate machines and motors of various shapes and sizes.

ROBERT E. MANLEY.
